UNITED STATES PATENT OFFICE.

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY.

MINE CAR.

Application filed May 15, 1925. Serial No. 30,540.

In the drawings:

Fig. 1 is a side elevation of a mine car constructed in accordance with this invention, parts being broken away at one end in order 5 to show an end of the drawbar, a coupling member and a bumper more clearly;

Fig. 2 is a transverse section of the car shown in Fig. 1 taken on the line 2—2 of Fig. 3;

10 Fig. 3 is a top plan view of the mine car shown in Fig. 1; and

Fig. 4 is a partial front elevation of the end gate.

This invention relates to mine cars and 15 has as an object to provide an improved mine car of composite construction having side sills connected together to form a rigid frame for the car. It is also an object to provide an improved means for bracing the 20 side sills and side floor portions of the car. It is also an object to provide an improved braking means for a car of the type specified.

With these and other objects in view, a 25 mine car constructed in accordance with this invention comprises, as shown in the drawings, Z-shape side sills 2 having the webs 3 vertical, the top flanges 4 projecting outwardly and the bottom flanges 5 projecting inwardly. While the side sills are shown as formed of pressed members, it is to be understood that they may be formed of suitable rolled shapes. To the side sills 2 are secured journal boxes 7 in which are mounted the 30 axles 9 carrying wheels 10, the journal boxes having their tops shaped to receive the side sills and having flanges bolted to the flanges of the sills. To the upper flanges 4 of the side sills 2 are secured metal sheets 12 which 35 form the outwardly projecting side floor portions 14 and are bent upwardly to form the sides 15 of the car, the upper edges of the sides being turned over inwardly to form re-enforced upper edges 16.

40 At the ends of the car and adjacent to the wheels 10, strap braces 18, which extend from the edge 16 of one side to the edge 16 of the other side, are secured to the sides and side floor portions and to the bottom flanges 45 of the side sills 2.

45 At the center of the car, a channel-shape tie member 20 having laterally projecting flanges 22 extends from one side to the other of the car, its flanges 22 being fastened to 50 the bottom flanges 5 of the side sills 2 and its

ends bent upwardly so that the flanges 22 contact with the side floor portions 14 of the sheets 12 and to which the flanges 22 are riveted. At each end of the tie 20, braces 23 are secured to the sides 15 of the car and to 60 the webs 24 of the ties 20.

Mounted on the braces 18 and tie 20 and extending longitudinally of the car at its center is an inverted U-shape drawbar or buffer beam 26 having outwardly projecting 65 flanges 27 which are riveted to the braces 18 and the flanges 22 of the tie 20. Between the drawbar 26 and the side sills 2 are planks 29 which are bolted to the braces 18 and tie 20 and which, with the web 30 of the drawbar 26, form the center floor portion of the car. The planks 29 are gained along one edge to receive the flanges of the side sills and drawbar and with the drawbar 26 project beyond the end braces 18, the length of 70 the planks and drawbar increasing gradually from the side planks to the drawbar to 75 form a curved center bumper for the car.

To the planks 29 and drawbar 26 are secured bumpers 32 having top plates 34 which 80 rest on the tops of the planks 29 and on the web 30 of the drawbar 26 and bottom plates 35 which are spaced from the top plates 34 sufficient distance to permit insertion of the fillers 36 between the bottom plates 35 and 85 the bottom of the planks 29 and flanges 27 of the drawbar 26. Both the upper and lower plates 34 and 35, respectively, of the bumper and the filler 36 extend inwardly to the rear edges of the end braces 18, the fillers 36 being cut away to receive the end braces 18. The upper and lower plates 34 and 35, respectively, are joined by an end plate 37 which is curved slightly to conform to the curvature of the planks 29. The web 30 of the drawbar 26 is reinforced at its ends by plates 40 and also has secured thereto coupling members 42 which fit over the upper plates 34 of the bumpers 32 and have their outer ends spaced from the bumpers sufficiently to provide openings for the usual coupling links. The coupling members 42, the bumpers 32, the drawbar web 30 and fillers 36 are provided with aligned openings to receive the usual coupling pins 38.

At one end the body is closed by a swinging end gate 45 comprising a corrugated sheet 47 pivotally mounted at 49 on the car sides 15 by means of the arms 48 and provided with an operating hook 50 formed

on the upper end of strap 53. The sheet 47 is reenforced at the sides by angles 51 and is provided at the bottom with an angle 52 to which the angles 51 and strap 53 are connected. The angle 52 extends from side to side of the sheet 47 and is bent upwardly at the center about an opening which is provided in the sheet 47 to receive a coupling member 42. At its other end the body is closed by a fixed corrugated end sheet 60 having flanges 61 which overlap and are secured to the end braces 18, and side sheets 15. The sheet 60 has a bottom flange 62 formed of an angle which rests upon and is secured to the planks 29 and side floor portions 14 of the car by bolts and rivets which engage the end brace 18.

The side floor portions 14 are provided with wheel openings 65 covered by wheel hoods 66 riveted to the side floor portions by rivets 67 and secured to the side sills and journal boxes by bolts 68 and to the planks 29 and journal boxes by bolts 69. To the side sills 2 are secured brackets 70 in which is rotatably mounted a shaft 71 having crank arms 72 to which are pivotally connected brake bands 73 which have their other ends adjustably connected to brackets 74 mounted on the adjacent brace 18. At one end shaft 71 is provided with a crank arm 75 connected by a link 76 to a bell crank lever 77 pivotally mounted in a bracket 78 secured to the side floor portion of the car. The bell crank lever 77 is connected by a link 80 to an operating lever 81 pivotally mounted in a bracket 82 connected to the fixed end sheet 60 of the car. The lever 82 is provided with a lug 84 which is adapted to engage in the teeth 85 formed in the guide bracket 86 mounted on the end sheet 60 to retain the brake lever in its adjusted position.

What is claimed is:

1. In a mine car, flanged side sills, side floor portions secured to flanges of said side sills and having upwardly bent portions forming the car sides, a U-shape member having outwardly projecting flanges connected to flanges of said side sills and said side floor portions and reenforcing members for said car sides connected to the web of said U-shape member.

2. In a mine car, side sills, side floor portions secured to said side sills and having upwardly bent portions forming the car sides, a tie member having outwardly projecting flanges connected to said side sills and side floor portions and reenforcing members secured to said car sides and the web of said tie members.

3. In a mine car, side sills having vertical webs and top and bottom flanges, side floor portions secured to said top flanges, a channel-shape tie member having outwardly projecting flanges connected to said side floor portions and said side sill bottom

flanges and a center floor portion between said side sills and secured to said flanges of said tie members.

4. In a mine car, side sills having vertical webs and top and bottom flanges, side floor portions secured to said top flanges and having upwardly bent portions forming the car sides, a channel-shape tie member having outwardly projecting flanges connected to said side floor portions and said side sill bottom flanges, a center floor portion between said side sills and secured to said flanges of said tie member and reenforcing members for said car sides connected to the web of said channel-shape tie member.

5. In a mine car, side sills having vertical webs and top and bottom flanges, side floor portions secured to said side sill top flanges and having upwardly bent portions forming the car sides, a channel-shape tie member having outwardly projecting flanges secured to said side floor portions and said side sill bottom flanges and reenforcing members for said car sides secured to the web of said channel-shape tie member.

6. In a mine car, side sills, side floor portions secured to said side sills, and a channel-shape tie member having outwardly projecting flanges secured to said side sills and side floor portions.

7. In a mine car, side sills having top and bottom flanges, side floor portions secured to said side sill top flanges and a channel-shape tie member having outwardly projecting flanges secured to the bottom flanges of said side sills and to said side floor portions.

8. In a mine car, side sills having vertical webs and top and bottom flanges, side floor portions secured to said top flanges and a channel-shape tie member having laterally projecting flanges connected to said side floor portions and side sill bottom flanges.

9. In a mine car, side sills having vertical webs and top and bottom flanges, side floor portions secured to said top flanges extending thence directly outwardly and having upwardly bent portions forming the car sides and reenforcing members secured to said side and side floor portions and said side sill bottom flanges.

10. In a mine car having a drawbar, a swinging end gate notched to receive said drawbar and an angle bar reenforcing the bottom edge of said gate, said angle bar being bent upwardly at said notch and having one flange secured to said gate and the other flange projecting outwardly from said gate.

11. In a mine car having a drawbar, a swinging end gate notched to receive said drawbar and an angle bar reenforcing the bottom edge of said gate and bent upwardly at said notch.

12. In a car structure, a body having a

- bottom, side walls, and end walls, said bottom comprising an intermediate section formed of longitudinally extending floor boards and side sections formed of metallic plates having their inner side portions terminating short of the intermediate section and their outer side portions forming said side walls, Z-bars extending along the side faces of the intermediate section and having their upper flanges secured to the under faces of the side sections and their lower flanges extending beneath the intermediate section, and braces connected with said side walls, the lower flanges of said Z-bars and to the intermediate section. 10
13. In a car structure, a body having a bottom, side walls, and end walls, said bottom comprising an intermediate section formed of planks and side sections, the side sections being formed of metallic plates integral with said side walls and their inner side portions terminating short of the intermediate section, Z-bars extending along the sides of the intermediate section and having their upper flanges secured to the under faces of the side sections and their lower flanges extending beneath the side portions of the intermediate section and braces connected with the side walls, said lower flanges of the Z-bars and to said intermediate section. 20
14. In a car structure, a body having a bottom, side walls and end walls, said bottom comprising an intermediate section formed of longitudinally extending floor boards and side sections formed of metallic plates having their inner side portions terminating short of the floor boards of the intermediate section and their outer side portions extending upwardly to form the side walls, Z-bars extending along the sides of the intermediate section and having their lower flanges extending beneath the intermediate section and their upper flanges extending beneath the side sections, means securing the Z-bars to the side sections and to said intermediate section, and braces extending beneath said bottom and secured to the intermediate and side sections thereof and having upstanding arms constituting posts secured against the outer faces of said side walls. 30
15. In a car structure, a body having a bottom, side walls and end walls, side sills in the plane of said bottom, said bottom comprising an intermediate section formed with planks and side sections, the side sections being formed of metallic plates having their outer side portions extending upwardly to form said side walls and their inner side portions connected with the intermediate section, the side sections intermediate the length of said body being cut out to provide wheel pockets for receiving wheels and wheel hoods connecting said side and intermediate floor sections. 40
16. In a car structure, a body having a bottom, side walls and end walls, said bottom comprising an intermediate section and side sections, the side sections being formed of metallic plates their outer vertical portions forming said side walls and their inner side portions connected with the intermediate section, the side sections intermediate the length of said body being cut away to provide wheel pockets and side sills in the plane of said intermediate bottom sections. 50
17. In a mine car having a central wood floor portion and side metal floor portions, the latter provided with wheel openings, side sills below said side metal floor portions of wheel hoods covering said openings and being provided with flanges serving as connecting means for said wood and metal floor portions. 60
18. In a mine car, Z-shaped side sills, a central wood floor portion resting on the lower flanges of said sills, metallic side floor sections resting on the upper flanges of said sills and wheel hoods connecting the central and side floor sections and said side sills. 70
19. In a mine car having a stationary central wood floor portion, side sills in the general plane thereof, side metal floor portions lapping said sills and central wood floor portion and a rigid brace directly connecting the side floor portion, the central floor portion and said sills. 80
20. In a mine car having a central wood floor portion, side sills in the general plane thereof, side metal floor portions having wheel openings therein, and lapping the central wood floor portion, and wheel hoods covering said openings and lapping said sills. 90
21. In a mine car having a central wood floor portion, side sills in the general plane thereof, side metal floor portions having wheel openings therein, and lapping the central wood floor portion, and wheel hoods covering said openings and lapping said sills and said central wood portion and securing means penetrating the wheel hoods and said central wood floor portion. 100

In witness whereof I have hereunto set my hand.

VICTOR WILLOUGHBY.
